(57) **CLAIM**

The ornamental design for a display screen with graphical user interface of a gaming machine as shown and described.

DESCRIPTION

FIG. 1 is a front view of a display screen with graphical user interface of a gaming machine showing our new design; FIG. 2 is a front view of a display screen with graphical user interface of a gaming machine showing an alternate embodiment our new design; and, FIG. 3 is a front view of a display screen with graphical user interface of a gaming machine showing another alternate embodiment our new design.

The broken lines showing of the display screen with graphical user interface of a gaming machine is included for the purpose of showing portions of the article which form no part of the claim.

1 Claim, 3 Drawing Sheets

FIG. 1

FIG. 2

FIG. 3
